INSERT TYPE DRILL BIT

Raymond D. York, San Angelo, Tex., assignor to
Walton Hale, El Paso, Tex.

Filed Sept. 12, 1961, Ser. No. 137,659

6 Claims. (Cl. 175—408)

This invention comprises a novel and useful insert type drill bit and more particularly pertains to a drill bit construction having longer life and a greater effectiveness for drilling well bores particularly in hard rock of the cavernous type.

It is well known in the drilling art and particularly in the drilling of deep well bores that the operation of the drill must be discontinued from time-to-time in order to resharpen or replace the worn teeth of a drill or substitute a new drill when this condition occurs. Inasmuch as the body of the drill is still fit for further service, it is obviously uneconomical to discard the complete drill. On the other hand, a serious monetary loss not to mention other undesirable conditions occur when it is necessary to suspend the drilling operation for the purpose of withdrawing the drill from the well bore and reconditioning or replacing the drill bit or the teeth thereof. Further, in drilling through hard rock and of a character having cavernous regions therein, when the drill bit breaks through the overlying material into such cavernous region, frequently due to the incline of the formation at the bottom of the open space penetrated by the drill bit the drill will strike and engage only at one portion thereof. Due to the weight of the drill, this frequently results in the teeth at that portion of the drill bit being embedded in the formation to too great a depth so that upon the turning moment being applied to the drill by the usual rotary table at the surface, the teeth thus excessively embedded tend to break off or at least wear unduly rapidly.

It is therefore the primary object of this invention to provide a drill bit construction which will satisfactorily overcome the aforementioned difficulties.

A further important object of the invention is to provide a drill bit construction having upon the cutting face of the drill body a firmly secured annulus or ring or attachment with a flat lower annular surface upon which insert drilling elements constituting drill teeth are secured and embedded, the ring serving as a carrier for the insert teeth, as a gauge means limiting penetration of the teeth into the ground thus preventing excessive penetration of the teeth, and as a stabilizing and guide means for the drill body in the well bore.

Another object of the invention is to provide a drill bit construction in which a conventional type of rock drill having the usual centrally disposed dependent cutting teeth has attached thereto upon a shoulder means comprising shoulders formed at the peripheral portion of the cutting face of the drill an annulus to which are secured replaceable insert teeth.

Yet another purpose of the invention is to provide a drill bit construction in which conventional drills may be readily modified by providing thereon and securing rigidly thereto a ring comprising both a gauge means to limit penetration of the drill teeth, a support for a series of replaceable insert teeth and a stabilizer and guide for the drill body in the well bore.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a view in vertical section through a portion of an earth formation showing the drilling of a well bore therein in accordance with the drill bit construction

2

of this invention, the showing in full lines being that of normal drilling operations while in dotted lines is shown the operation of this invention upon drilling into cavernous portions of the formation;

5 FIGURE 2 is an end elevational view from the lower end of the drill bit construction of this invention;

FIGURE 3 is a vertical central sectional view through the drill bit, being taken substantially upon the plane indicated by the section line 3—3 of FIGURE 2; and

FIGURE 4 is an exploded perspective view of the drill bit, the gauge and mounting ring and the insert drilling elements carried by the latter.

Referring first to FIGURE 1, it will be observed that the numeral 10 indicates a portion of a formation into which is being drilled a well bore 12 by means of the usual drilling string 14 having at the lower end thereof a drill bit construction 16 in accordance with the present invention. As suggested in FIGURE 1, the well bore is continued down into the formation until it penetrates into a cavern or crevasse 18 through which it is desired to continue the well bore as indicated in dotted lines at 20. As the drill bit breaks through the upper wall or surface 22 of the cavern or crevasse, it will drop until it engages the inclined bottom wall 24 thereof. In conventional bits, when this condition occurs, the weight of the drilling string is borne entirely by a relatively few of the teeth which first engage the surface 24 so that these teeth may become embedded too deeply, thus taking too big a bite from the rock formation thereby breaking the teeth or causing serious damage thereto.

The drill bit construction of the present invention, as shown in FIGURES 3 and 4, comprises the usual drill body 30 having an externally threaded upwardly and inwardly tapered neck 32 by which it is removably secured to the correspondingly tapered internal thread of the lowermost section or drilling collar of the drilling string 14. As will be noted, the stem 32 is hollow having an axial passage 34 therethrough by means of which air or the usual drilling fluid is circulated downwardly through the drill string and drill bit, then across the bottom wall of the well bore and then upwardly of the well bore in the annular space between the latter and the drilling string to the surface.

45 Circumferentially spaced, radially extending and downwardly projecting drill teeth 36 are provided upon the lower or cutting face of the drill bit. Since these teeth may be of any conventional construction, a further description of the same is deemed to be unnecessary. In accordance with this invention, however, the peripheral portion of the cutting face of the drill body is provided with notches or shoulders 38 which lie in a common plane which is transverse to and perpendicular to the longitudinal axis of the drill body. Seated upon the shoulders 38 is a ring or annulus 40 which as shown in FIGURE 3 is fixedly secured thereto as by welding 42. This annulus is of sufficient size and has a central opening 44 therethrough of sufficient size to surround the previously mentioned teeth 36 which latter project downwardly below the annulus to provide the axial or central or pilot portion of the drill. Preferably the cylindrical exterior surface of the annulus projects radially outwardly beyond the body 30 as shown in FIGURES 1 and 3 in order to thus constitute a stabilizing and guide means for holding the drill body centrally in the well bore and in straight alignment with the latter.

60 The lower surface of the ring or annulus 40 constitutes a flat annular surface 46 which constitutes a gauging surface for the drill bit construction as set forth hereinafter. Formed at spaced intervals circumferentially of the surface 46 are a series of downwardly projecting lugs 48 together with radially extending notches 50 formed at the vertical face 52 of these lugs. A series of insert cutting

elements 54 are received in these notches 50 and lie flush against and are reinforcingly supported by the flat surface 52 of the lugs 48, these inserts being firmly secured to the ring 40 in the usual manner as by welding or the like.

It should be here noted that the present construction enables a relatively small number of drilling elements 54 of extremely hard cutting or abrasive material to be utilized since they are firmly supported in the notches 50 and against the face 52 of the lug 48. Thus, a relatively expensive material can be employed for the cutting elements 54 which would be not feasible for the entire structure of a drill bit.

It will be further understood that when replacement of the elements 54 becomes necessary, they can readily be removed from the ring 40 and replaced, or the entire ring may be removed from its seat upon the shoulders 38 of the drill body 30 and replaced with another sub-assembly of a ring with the cutting elements mounted therein.

The ring is so spaced with regard to the drill teeth 36 and the additional insert teeth 54 that the bottom surface 46 of the ring will constitute a gauge means limiting penetration of these teeth into the formation. In normal drilling, as shown in full lines in FIGURE 1, both the central teeth 36 and the insert teeth 54 will operate to drill the bore 12, with the ring 40 serving as a stabilizer to prevent cocking of the drill body in the well bore and also to center the drill with respect to the sides of the well bore. However, when the drill breaks into a cavernous or fissured formation 18, and the drill drops downwardly as shown in the dotted line position, the engagement of the flat surface 46 upon the surface 24 of the fissure will limit penetration of the teeth of the drill bit so that they will not take too great a bite and thus be broken or damaged. However, as the drilling continues, and the drill being maintained in its desired attitude with respect to the axis of the well bore, the drilling of the well bore will be resumed as at 20 in true alignment with the well bore 12.

It will be observed that the ring 40 thus serves a number of important functions. It provides a readily replaceable sub-assembly by which new sets of insert teeth may be applied to the drill body 30. In addition, it constitutes a gauge limiting penetration of the teeth into the formation so as to prevent excessive penetration with resultant breakage of the teeth. Still further, it constitutes a centralizer or stabilizer for the drill body in the well bore ensuring proper positioning of the drill in the bore. Still further, as shown by the passages indicated at 56 in FIGURE 3, there is provided a clearance between the inside perimeter within the opening 44 of the ring and the outer surface of the teeth of the drill body 30 to permit ready upward flow of drilling fluid from the bottom of the well bore past the bit construction and into the annulus surrounding the drilling string.

The foregoing is considered as illustrative only of the principles of the invention. Further, since numerous modifications and changes will readily occur to those skilled in the art, it is not desired to limit the invention to the exact construction and operation shown and de-

scribed, and accordingly all suitable modifications and equivalents may be resorted to, falling within the scope of the invention as claimed.

What is claimed as new is as follows:

- 5 1. A drill bit construction comprising a drill body having a lower end provided with a plurality of axially and radially extending wings with pilot teeth projecting downwardly therefrom, peripherally extending shoulder means on said wings surrounding and recessed into the radially outward portions of said wings, said shoulder means including planar horizontal and depending vertical convex surfaces, annular means comprising a ring having flat top and bottom surfaces and cylindrical outer and inner surfaces, said ring top and inner surfaces being respectively seated upon and secured to said shoulder means horizontal and vertical surfaces, said ring inner surface being spaced from some of said pilot teeth and thereby providing fluid flow passages between said ring and said body, insert elements comprising drill teeth secured to and projecting downwardly from said ring bottom surface.
- 10 2. The combination of claim 1 wherein said horizontal surfaces are flat and coplanar, said ring top surface including flat portions each seated upon a horizontal surface over the entire area of the latter, said ring inner surface engaging each vertical surface over the entire circumferential extent of the latter.
- 15 3. The combination of claim 1 wherein said bottom surface has a plurality of downward projections therefrom provided each with a plane vertical face, a plurality of notches extending upwardly into said ring from said bottom surface and each against a projection, said drill teeth being each seated and secured in a notch and having a vertical face disposed in face-to-face engagement with an associated projection face.
- 20 4. The combination of claim 1 wherein said outer surface is of greater diameter than that of said drill body and wings and constitutes the sole means of engagement with the wall of a well bore.
- 25 5. The combination of claim 1 including axially projecting cutting elements carried by said ring and projecting forwardly from said front annular surface, the radial outer edges of said elements comprising an axial extension of said cylindrical outer surface.
- 30 6. The combination of claim 5 wherein the radially inner edges of said elements project radially inwardly of said cylindrical inner surface.
